UNITED STATES PATENT OFFICE.

MATHEW G. IVANDICK, OF NORTH CHICAGO, ILLINOIS.

AUTOMOBILE SIGNAL.

Application filed April 18, 1922. Serial No. 554,775.

To all whom it may concern:

Be it known that I, MATHEW G. IVANDICK, a citizen of the United States, and resident of North Chicago, in the county of 5 Lake and State of Illinois, have invented certain new and useful Improvements in Automobile Signals; and I do hereby declare that the following is a full, clear, and exact description thereof.

10 The invention relates to automobile signals. It comprises a casing partitioned into two compartments, a plate in one compartment having the word "Stop" cut therethru, an electric lamp for illuminating the plate and making the word "Stop" visible at night, and plates pivoted in the other compartment having the words "Left" and "Right" cut therein thru which light is emitted from a lamp, the lamps being adapted 15 to be illuminated when the plates are thrown to operative signalling positions.

20 A primary object of the invention is the provision of signals plainly visible in the day time, the plates being conveniently disposed to signal to the operators of following cars, and which are illuminated at night time, the electric lamps being lighted simultaneously with the movement of the plates to visible position. The plates occupy but 25 little space and the "Stop" sign may be conveniently revealed either alone or simultaneously with a "Left" and "Right" sign.

30 An important object is the convenience of operation of the device, the "Stop" signal being thrown on alone by depression of the brake pedal or simultaneously with a "Left" or "Right" signal by the convenient manipulation of a lever disposed within the reach of the driver. Springs are provided for 35 automatically restoring the plates to normal inoperative positions, restoration of the plates to these positions being concomitant with a breaking of the electric circuits so that the lamps are extinguished.

40 With the above and other objects in view which will appear as the description proceeds, my invention resides in the novel construction, combination and arrangement of parts substantially as hereinafter described.

45 and more particularly defined by the appended claims, it being understood that such changes in the precise embodiment of the herein disclosed invention may be made as come within the scope of the claims.

50 55 In the accompanying drawing, I have illustrated one complete example of the phys-

ical embodiment of the present invention constructed according to the best mode I have so far devised for the practical application of the principles thereof, and in 60 which:

Figure 1 is a vertical cross sectional view thru the signal.

Figure 2 is a rear elevation with parts broken away.

Figure 3 is a diagrammatic view representing the disposition of the cables and cooperative parts, and

Figure 4 is a diagrammatic view showing the arrangement of the electric leads.

Housing 10, having rectangular sides, is secured to conveniently disposed support 11, and has bosses 12 outwardly directed from the front side receiving lamps 13 and 14. The rear side is cut away to form openings 15 and 16. Above opening 15, shaft 17 is mounted conveniently for rotation having a contact arm 18 rigid therewith, adapted to cooperate with contact plate 19 on side 20. Shafts 21 and 22 are similarly provided with contact arms 23 and 24, adapted to cooperate with contact plate 25. Partition 26 forms two compartments in the housing.

Carried by lugs 27, rigid with shaft 17 is a stop plate 28, having the word "Stop" cut out therefrom. Shafts 21 and 22 in a similar manner carry plates 29 and 30 respectively, for signalling "left" and "right" respectively. Pulley 31 is rigid with shaft 90 17 and at a point on the periphery thereof, cable 32 is secured, which extends downwardly over pulley 33 and rearwardly thru an opening in a frame 34 supported pivotally at 35, the cable having a stop 36 thereon immediately adjacent the frame. Connected to the cable is a spring 37 secured to brake lever 38. On the depression of the brake lever, cable 32 is tensioned, rotating pulley 31 and shaft 17, and moving plate 28 downwardly at the same time causing arm 18 to contact with plate 19. This closes an electric circuit formed by battery 39, lead 40, lamp 41, lead 42, contact plate 19, contact arm 18, and lead 43, lead 43 being 95 grounded at 44 and lead 45 from battery 49 being grounded at 46.

If the stop plate 28 reaches its operative position before brake lever 38 reaches its lowermost position, spring 37 will expand. On the restoration of brake lever 38 to its normal inoperative position, spring 47 se-

cured to bearing 48, and to shaft 17 rotates the shaft moving plate 28 to upper inoperative position. This breaks the electric circuit and extinguishes the lamp. It is not necessary that the lamp be used in the day time, as plate 28 will be readily visible.

Shaft 21 may be rotated in a manner somewhat similar to shaft 17, by means of pulley 49, to which cable 50 is secured which leads over pulley 51 and extends thru an opening to frame 34, being provided adjacent the opening with a stop 52. Cable 50 leads over sheave 53 to arm 54, pivoted at 55 and having handle 56 rigid therewith. Moving handle 56 to the left, lifts arm 54 and brings stop 52 against frame 34, tensioning spring 57 secured to the frame, and moving the frame against stop 36, so that cables 50 and 32 are tensioned. This results in moving pulleys 31 and 49, and moving plates 28 and 29 downwardly, displaying "stop" and "left" signals. Arm 23 is thus brought against contact plate 25 and current is directed from battery 39 through leads 40 and 58, lamp 14, lead 59, contact plate 25, contact arm 23, lead 60 and lead 43. Thus lamps 13 and 14 are simultaneously illuminated. The release of lever 56 permits plates 28 and 29 to return to their normal elevated inoperative positions under the influence of springs 47, spring 57 restoring frame 34 to its normal position. When lever 56 is moved to the right, cable 61, secured to arm 62, rigid with the lever and extending over sheave 63, is tensioned, thus bringing stop 64 on cable 61 against frame 34.

As cable 61 is secured to pulley 65, which is rigid with shaft 22, the shaft is rotated on the tensioning of the cable, and right plate 30 is elevated, contact arm 34 being brought against contact plate and closing an electric circuit illuminating lamp 14. In this operation, frame 34 is brought against stop 36, and stop plate 28 is also moved to signalling position, lamp 13 being also illuminated.

It is therefore apparent that by the mere depression of the brake pedal, the stop plate will be made visible and lamp 13 illuminated, and that by the proper manipulation of the handle 56, the left or right plates may be moved to visible position, stop plate 28 being also operated and lamps 13 and 14 illuminated.

I claim—

The combination of a housing, a partition dividing said housing into two compartments, a stop plate pivoted in one of said compartments, left and right plates pivoted in the other of said compartments, an electric lamp in each of said compartments, means for moving the stop plate to visible position and illuminating one of said lamps to make said stop plate visible, and means for moving either of the left and right plates to visible position, and simultaneously moving said stop plate to visible position and illuminating both of said electric lamps.

In testimony that I claim the foregoing I have hereunto set my hand at North Chicago, in the county of Lake and State of Illinois.

MATHEW G. IVANDICK.
